UNITED STATES PATENT OFFICE

2,666,382

PARQUETRY DESIGN ASPHALT TILE DIE

Harry A. Hachmeister, Pittsburgh, Pa.

Application February 1, 1951, Serial No. 208,897

1. Claim. (Cl. 101—30)

1 This invention relates to stamping dies of the type having cutting or shearing and marking blades in combination with resilient ejecting means positioned between the blades, and in particular a multiple die having lower shearing elements adjustably mounted on the sides of blocks with upper shearing blades and design forming elements carried by an upper shoe, positioned to coat with the lower cutting bars and having blocks of sponge rubber positioned between the elements for ejecting the stamped elements from the dies.

The purpose of this invention is to provide means for stamping asphalt tile units from sheet material with the units of tile cut and impressed with designs simultaneously and with one operation.

It is difficult to cut asphalt tile with stamping dies of the enclosed type where the four edges are cut simultaneously because the asphalt clings to the dies and it is also difficult to impress designs in the surface of asphalt units because it is difficult to accurately position the units after they are cut. With this thought in mind this invention contemplates an improved method of incorporating design impressing units in combination with cutting knives and providing blocks of sponge rubber between the cutting elements and impressing units whereby the tile units are positively ejected from the dies as soon as the upper dies leave coating lower dies.

The object of this invention is, therefore, to provide means for mounting coacting dies in shoes of a punch press whereby designs are impressed in units and the units are cut from sheet material with one operation.

Another object of the invention is to provide means in an upper die for cutting and impressing designs in asphalt tile whereby the tile is ejected from the dies as soon as the dies separate.

Another object of the invention is to provide means in an upper die having cutting blades on four sides with impressing die elements between the blades for mounting sponge rubber blocks between the impressing die elements and blades.

A further object of the invention is to provide a combination die for simultaneously impressing designs in and cutting asphalt tile from sheet material which is of a simple and economical construction.

With these and other objects and advantages in view the invention embodies a lower shoe having lower cutting bars adjustably mounted in the sides of blocks and with stripper elements positioned between the blocks, and an upper shoe

2 having upper cutting blades, design impressing blades and sponge rubber blocks positioned between the blades, mounted to register with cutting bars of the lower shoe.

5 Other features and advantages of the invention will appear from the following description taken in connection with the drawings wherein:

Figure 1 is a view looking upwardly taken on line 4—4 of Figure 3 showing a plurality of squares with design impressing blades positioned between the cutting knives and with sponge rubber blocks positioned between the blades and also between the blades and cutting knives.

Figure 2 is a similar view looking downwardly taken on line 2—2 of Figure 3 showing the lower cutting bars and stripper frame.

Figure 3 is a front elevational view showing the parts assembled and showing the upper shoe with the upper knives thereon spaced from the lower cutting bars of the lower shoe.

Figure 4 is a detail on an enlarged scale taken on line 4—4 of Figure 2 showing the position of the dies at the end of the cutting stroke.

Figure 5 is a similar view taken on line 5—5 of Figure 2 showing the upper dies in the upper position wherein the dies are spaced from the lower dies of the lower shoe.

Figure 6 is a similar section showing the meeting edges of two of the dies and with the knives of the upper shoe actuated through the cutting and impressing operation.

Figure 7 is a detail showing a section through the mounting of one of the design impressing blades.

Figure 8 is a detail showing parts of the stripper frame with parts broken away.

Figure 9 is a cross section through the stripper frame taken on line 9—9 of Figure 8.

Figure 10 is also a cross section through the stripper frame taken on line 10—10 of Figure 8.

Figure 11 is a detail illustrating a modification wherein a backing blade is inserted between the design forming plate or blade and a shoe for forming tile of a different thickness.

Referring now to the drawings wherein like reference characters denote corresponding parts the asphalt tile stamping die of this invention includes an upper shoe 10 having a plurality of squares thereon with upper cutting knives 11 positioned around the squares and with design impressing blades 12 between the said knives, and a lower shoe 13 having lower cutting bars 14 positioned around the edges of squares corresponding to the squares of the upper shoe and having a stripper frame including longitudinally disposed

bars 15, 16, 17 and cross bars 18 and 19 at the ends and also intermediate cross bars 20, positioned around the lower cutting bars.

The lower shoe 13 is provided with extensions 21 and 22 and posts 23 and 24, positioned on the extensions extend through openings 25 and 26 on similar extensions 27 and 28 of the upper shoe. The extensions 27 and 28 of the upper shoe are provided with depending sleeves 29 and 30, respectively that provide guides for holding the upper shoe in position upon the posts.

The lower dies of the lower shoe are formed with a plurality of master blocks 31 that are secured to the shoe by cap screws 32 and the lower cutting bars 14 are secured to the blocks 31 by cap screws 33 that extend through slotted openings 34. The openings 34 are provided with countersunk outer ends 35 in which heads 36 of the cap screws 33 are positioned.

Rubber stripper return strips 37 with concave surfaces 38 and 39 in the sides are positioned at the sides of and between the blocks 31 and the stripper frame, which is held against the strips 37 by countersunk head screws 40. The screws 40 are threaded into the lower shoe 13 with lock nuts 41 provided on the screws for retaining the screws in adjusted positions.

With the parts formed in this manner the lower cutting bars are positioned against the sides of the master blocks 31 with the cutting bars at the sides extended over the ends of the cutting bars on the ends of the blocks.

The stripper frame including extensions 15, 17, 18 and 19 and also the intermediate strips is positioned on the upper ends of the rubber stripper return strips 37 and in the cutting action the strips move downwardly as shown in Figures 4 and 6.

The upper shoe 10 is provided with a plurality of master blocks 42 for the upper dies and the blocks 42, which are attached to the shoe by cap screws 43, are positioned directly above the master blocks 31 of the lower shoe. The upper knives which are indicated by the numeral 11 and which have elongated slots 44 therein are attached to the sides and ends of the blocks 42 by cap screws 45, heads 46 of which are positioned in counterbores 47 around the outer ends of the openings 44.

Strips for impressing lines or designs in the asphalt tile are also carried by the lower face of the block 42 and, as illustrated in Figures 4 and 5 the strips, or blades 12 having V-shape lower ends 49 are secured to bars 50 by cap screws 51 and the bars 50 are secured to the block 42 by cap screws 52.

As illustrated in Figures 1 and 5 the blades 12 are equally spaced in the sections of the die and the blades at the center are separated by a sponge rubber block 53, the intermediate part of which is cemented to a plate 54 and the plate is secured to the under surface of the master block 42 by screws 55. The corners of the block 53 are provided with recesses 56 and 57 which provide clearance for the heads of the cap screws 51.

The intermediate blades are separated by sponge rubber blocks 58 and 59, the upper surfaces of which are provided with recesses 60 and 61, respectively, and the inner surfaces 62 and 63, respectively are cemented to the under surfaces of the mounting bars 50. The outer edges of these blocks are also provided with recesses 64 and 65 to provide clearance for the heads of the cap screws 51.

The intermediate blades are also separated

from the cutting knives 11 by blocks 56 and 57, the upper surfaces of which are provided with recesses 68 and 69, respectively which receive the mounting bars 50 through which the blocks are cemented.

The block 56 is provided with corner pads 70 and 71 and the block 57 is provided with similar corner pads 72 and 73 which extend beyond the outer surfaces of the blocks 56 and 57 to insure forcing the tiles from the upper dies.

As illustrated in Figure 6, each of the mounting bars 50 is provided with two dowel pins 74 that extend into openings 75 in the master block 42 for locating the bars. These pins are located in different positions on each bar and with the bars numbered accordingly the bars will be returned to the correct position.

The bars of the stripper section are formed of two strips of material and the strips are secured together by rivets 76, the ends of which are peaned over, as illustrated in Figures 9 and 10 so that the upper and lower surfaces of the bars are smooth. The intermediate bars are provided with bevel edges, as indicated by the numeral 77. The inner edges of the end bars 17 are also beveled, as indicated at the point 78.

In the design illustrated in Figure 11 a backing sheet 79 is positioned between the mounting bars 50 and the upper shoe 10 and with this shoe positioned between the lower edges of the blades 48 and the master block 31 and the thickness of the backing shoe corresponds with the thickness of the tile being formed with the dies.

With the parts formed in this manner a sheet 35 of material, as indicated by the numeral 80, is fed across the lower shoe and with downward movement of the upper shoe the squares are stamped from the sheet with the lower V-shaped edges of the blades 48 impressing lines in the surface of the sheet.

It will be understood that with impressing elements formed in different patterns or different shapes, different designs may be impressed into the surface of the asphalt tile and with the parts arranged in this manner designs are impressed 45 simultaneously with the cutting action, and as the upper shoe carries the upper dies upwardly the sponge rubber strips the finished sections from the dies whereby these sections, with the remaining material from which the sections are stamped, are removed from the dies and a new sheet positioned therein.

With the lower cutting blades and upper cutting knives provided with vertically elongated slots in which the mounting cap screws are positioned the die members or cutting elements are vertically adjustable on the master block and wear developing in the cutting edges may be compensated for. Furthermore with the blades 48 independently mounted on the mounting bar 50, these blades may be independently removed, sharpened and replaced.

It will be understood that modifications may be made in the design and arrangement of the parts without departing from the spirit of the invention.

What is claimed is:

In a tile making die, an upper shoe having a plurality of squares thereon, cutting knives positioned around the squares, design impressing 70 blades arranged between said knives and having V-shaped lower ends, a lower shoe having squares thereon and provided with cutting bars positioned around the edges of the squares, a stripper frame 75 on said lower shoe including longitudinally ex-

tending bars, cross bars extending between said longitudinally extending bars and secured thereto, extensions on said upper and lower shoes provided with openings, posts extending through said openings, sleeves depending from the extensions on said upper shoe providing guides for said posts, master blocks secured to said lower shoe, said cutting bars being provided with a plurality of slots terminating in countersunk outer ends, cap screws extending through said slots and having heads positioned in said countersunk outer ends, resilient return strips having concave surfaces positioned between said blocks, a plurality of master blocks secured to said upper shoe and positioned directly above the blocks in said lower shoe, a plate secured to the undersurface of the master blocks on the upper shoe, sponge rubber blocks

secured to said plate, and corner pads secured to the ends of certain of said sponge rubber blocks.

HARRY A. HACHMEISTER.
